GAUGE FOR PRECIOUS STONES

William H. Lehrfeld, Freeport, N. Y.

Application February 1, 1950, Serial No. 7,622

Term of patent 14 years

(Cl. D52—1)

To all whom it may concern:

Be it known that I, William H. Lehrfeld, a citizen of the United States, residing in Freeport, Long Island, in the county of Nassau, State of New York, have invented a new, original, and ornamental Design for a Gauge for Precious Stones, of which the following is a specification, reference being had to the accompanying drawing, forming a part hereof, in which:

Fig. 1 is a top plan view of a gauge for precious stones embodying my new design.

Fig. 2 is a side elevation thereto.

Fig. 3 is a bottom plan view thereof.

I claim:

The ornamental design for a gauge for precious stones, as shown.

WILLIAM H. LEHRFELD.
